UNITED STATES PATENT OFFICE.

FRANK HEDLEY, OF YONKERS, AND JAMES S. DOYLE, OF NEW YORK, N. Y.

CAR SEAT AND DOOR ARRANGEMENT.

1,074,862.

Specification of Letters Patent.

Patented Oct. 7, 1913.

Application filed February 12, 1910. Serial No. 542,502.

To all whom it may concern:

Be it known that we, FRANK HEDLEY and JAMES S. DOYLE, both citizens of the United States, and respectively residing at Yonkers, county of Westchester, and State of New York, and city, county, and State of New York, have made a certain new and useful Invention in Car Seat and Door Arrangements, of which the following is a specification.

This invention relates to seat and door arrangements for street or railway passenger cars.

The primary object of the invention is to provide means for facilitating and expediting the loading and unloading of passengers in the operation of surface, subway, elevated, or other street or railway cars.

A further object is to provide a combined seat and door arrangement whereby when the door is not required for use the space immediately in front of the same may be utilized for seating purposes, and when the door is in use the seats in front of the same are rocked or moved out of the way.

A further object is to provide means inside the car and adjacent a side door thereof, to separate the space leading to and from the doorway into separate passages of comparatively limited area.

Other objects of the invention will appear more fully hereinafter.

The invention consists substantially in the construction, combination, location and relative arrangement of parts all as will be more fully hereinafter set forth, as shown in the accompanying drawings, and finally pointed out in the appended claims.

Referring to the accompanying drawings, and to the various views and reference signs appearing thereon, Figure 1 is a view in vertical transverse section, parts broken off, of a car body showing the application of a car seat and door arrangement embodying the principles of our invention. Fig. 2 is a view in vertical section taken longitudinally of the car, on the line 2, 2, Fig. 3, looking in the direction of the arrows. Fig. 3 is a view in horizontal section on the line 3, 3, Fig. 1, looking in the direction of the arrows, and showing both sides of the car. Fig. 4 is a broken detail view in horizontal section of the door space separating

standards or uprights on one side of the car. Figs. 5 and 6, are broken detail views in section, showing forms of locking devices for holding the seat in raised or lowered position.

The same part is designated by the same reference sign wherever it occurs throughout the several views.

In the practical operation of handling the passenger traffic of street or other railway cars, the problem of facilitating and expediting the loading and unloading of the passengers has become a serious and important one, especially in the case of cars operating on limited time and headway schedules, and at points of heavy and congested traffic, as, for instance, at subway and elevated stations; busy street corners, or centers, or the like. The important consideration is to secure rapid transit, and the time consumed at a station, street corner, or the like, in unloading or taking on passengers if unduly extended in length, not only increases the time required to complete a trip of the car or train, but also seriously interferes with the time and headway schedules of other cars or trains of the system. Moreover, at the stations, street corners, or other stopping points where it is necessary to handle large crowds, the jam and crush of the passengers in attempting to enter and leave the car, causes material discomfort to the passengers, and frequently serious physical injury. Experience has shown that passengers after entering a car are prone to remain congested and crowded together at the ends of the car where the doors have ordinarily been located thereby making it difficult to force one's way through the crowd to leave the car upon arrival at a station or stopping place, or to get on the car, and hence, also, materially increasing the time during which the car or train must remain at the station or stopping point.

It is among the special objects and purposes of our present invention to overcome and avoid these and other objections encountered in the practical operation of street car and railway systems, and in carrying out our invention we propose to supply the cars with side doors, in addition to, and independently of the ordinary doors at the

ends of the car. These side doors we propose to locate at any convenient point in the length of the car, and on one or both sides thereof. We have found that the midlength 5 of the car is a suitable point for the location of the side doors, and we have shown, in Fig. 3, the side doors located on both sides of the car.

In practice we employ sliding doors but 10 our invention as defined in the claims is not to be restricted or limited in this respect. We also propose to employ a width of door opening of sufficient extent to enable the same to be divided into two entry or exit 15 ways each of sufficient area to accommodate the free passage of a single passenger, but not of sufficient area to enable one passenger to stand therein while another is entering or leaving the car therethrough. We also propose 20 to employ seats in connection with each of these entry or exit ways and which may be moved into position for use when the adjacent door is not in commission, and moved out of position for use as seats when the 25 door is required for use.

In the drawings reference sign 10, designates a door, which, in this instance, is shown as a sliding door, suspended on rollers 11, and operated in the usual or any well 30 known, suitable or convenient manner. As shown in Fig. 3, a door is arranged on each side of the car, and, as above indicated, these doors are additional to and independent of the usual end doors of the car, and are located 35 at any desired point in the length of the car, say, for illustration, at the midlength of the car. The doors are arranged to slide in a direction lengthwise of the car and, when in open position, are received in 40 pockets 12, in the side walls of the car.

Arranged within the car opposite each of the side doorways above referred to, are located means to divide the space inside the car leading to and from the adjacent side 45 door way into separate passages, indicated, generally, by reference signs A and B, Fig. 3, the area of each space A, B, being sufficient to enable a single passenger to pass freely therethrough, but not sufficient to permit 50 a passenger to stand therein while another is entering or leaving the car, therethrough. One form of means for separating the spaces inside the doors into separate 55 passages having the described characteristics is shown wherein standards 13, 14, 15, are provided opposite the points of mid-length of each doorway. These standards are secured to and rise from the floor of the car, and are arranged in line with each other 60 transversely of the car. The standards 13 and 14, extend to the roof of the car, while the standards 15 are bent at their upper ends and connected to the standards 14, next adjacent thereto, at a sufficient height to en-

able the guards at the ends of the car to 65 command a view of the side doorway. The adjacent standards 13, 14, are also desirably connected together at the same height, as indicated at 16. The standards 13, 14, 15, of each set are separated from each other a 70 convenient distance, and if desired, panels 17, may be interposed between adjacent standards, the paneling, however, only extending to the height of the cross connection 16, or the upper end of standard 15. If 75 desired the space between the standards 13, 14, above the cross connection 16, as well as the space between the standards 13 on the respective sides of the longitudinal central passage of the car, may be utilized as spaces 80 for advertising signs or panels, and without interfering with an unobstructed view from end to end of the car of the guards at the ends of the car. The inner standards 13 of the sets on respectively opposite sides of the 85 car are separated from each other a distance sufficient to afford room therebetween to enable passengers to pass. The outer standards 15, are positioned sufficiently close to the adjacent doors to prevent passengers 90 from crowding through the space between the doors and said standards when the doors are closed, even when the adjacent and associated seats are not in position.

To the door jambs on each side of the side 95 doorways or rather to the ends of the seats 18, extending along the sides and lengthwise of the car on opposite sides of each side doorway, are pivotally connected the seat sections 19, 20, as indicated at 21. These 100 seats are arranged to be swung down into position to form seats for passengers when the side doors are not in use and are closed, as indicated in full lines in Fig. 2, and in the upper portion of Fig. 3, and when in this 105 position the free ends of the seats rest on brackets 22, carried by the standards 14, 15. Ordinarily the side doors on only one side of the car, or the cars of a train are required to be in service. In that case the seats 19, 110 20, associated with the side door on the opposite side of the car or cars are rocked down into position to form passenger seats. On the side of the car where the doors are in use the seats are rocked or swung into 115 vertical position, as shown in full lines in Fig. 1, and in the lower portion of Fig. 3, and when in this raised position they form side rests at the ends of the longitudinal car seats 18. If desired means may be provided 120 for locking the seats 19, 20, in their raised position. In Figs. 1 and 5 a latch construction 25, is shown for this purpose. Similarly, locking means may be provided 125 for locking the seats in their lowered position. Such a locking means is indicated at 26, Fig. 6. In practice we prefer to arrange the locking means 26, to engage the door

when the seats are in their lowered position so that the door will be locked in closed position when the seat is lowered.

It is obvious that the doors 10, may be operated in any suitable, convenient or well known manner and the operation controlled from any convenient point. Inasmuch as devices for accomplishing the door movements and the control thereof are common and well known in the art we do not deem it necessary to show or describe the same herein, as they form no part of our present invention.

We have found in the practical application of a construction and arrangement such as above described, that the loading and unloading of passengers is thereby greatly facilitated and expedited, the time required to load and unload passengers even at points or stations where there is the greatest congestion is greatly reduced, and the crowding and jostling of passengers while getting on and off the cars is very largely reduced, as well as the danger of injury.

Having now set forth the object and nature of our invention, and a construction embodying the principles thereof, what we claim as new and useful and of our own invention, and desire to secure by Letters Patent is—

1. The combination with a car having a side door, of means arranged inside the door and extending transversely of the car to divide the space inside the door into separate passages, hinged seat sections for said passages, and means carried by the hinged seat sections for locking the door closed while said sections are in position for use.

2. The combination with a car having a doorway in each side thereof intermediate its ends, said side doorways being arranged to open into the body of the car at points opposite each other, of a door for each of said side doorways, and means arranged within the car and extending in a transverse direction partway across the car from a point approximately opposite the mid-width of each side doorway opening, to divide the space immediately inside said side doorways into separate passages, the passage separating means for one side doorway being spaced apart from that of the opposite side doorway to afford a passage therebetween longitudinally of the car.

3. The combination with a car having a doorway in the side thereof intermediate its ends, and opening into the body of the car, of a door for said side doorway means arranged inside the body of the car and extending transversely partway thereacross from a point approximately opposite the mid width of the side doorway to divide the car body space inside said side doorway into separate passages, and a movable seat sec-

tion arranged on each side of said passage 65 separating means to extend across said passages when in position for use.

4. The combination with a car having a doorway in the side thereof intermediate its ends and opening into the body of the car, 70 of a door for said side doorway, means arranged inside the body of the car and extending transversely partway thereacross from a point approximately opposite the mid-width of the side doorway to divide the 75 car body space inside the said doorway into separate passages, and a seat section hinged at each side of the side doorway and when in position for use extending transversely across said passages. 80

5. The combination with a car having a doorway in the side thereof intermediate its ends and opening into the body of the car, of a door for said side doorway, means arranged inside the body of the car and extending transversely partway thereacross from a point approximately opposite the mid-width of the side doorway, to divide the car body space inside the said doorway into separate passages, a bracket carried by 90 said passage separating means on each side thereof, a seat section hinged on each side of said side doorway and arranged, when in position for use, to extend across said passages and to be received and to rest on said 95 brackets.

6. The combination with a car having a doorway at the side thereof intermediate its ends, and opening into the body of the car, of a door for said side doorway, means arranged inside the car body and extending transversely partway thereacross from a point approximately opposite the mid-width of the said side doorway to divide the car body space inside said doorway into 100 separate passages, a seat section hinged at each side of the side-doorway, and arranged to extend across said passages when in position for use, and means for locking said seat sections in and out of position for use. 105

7. The combination with a car having a doorway in the side thereof intermediate its ends, of a door therefor, and posts extending vertically from the floor to the roof of the car and arranged in line with each other transversely of the car from a point appoximately opposite the midwidth of the side doorway, said posts carrying a panel between them. 115

8. In a passenger car provided with a 120 doorway, a door for said doorway, a seat movable into and out of position across said doorway and means for locking said door in closed position.

9. In a passenger car provided with an 125 opening, a door for said opening, a seat extending across said opening, and door locking means operatively related to said seat.

10. A passenger car provided with a door, a seat movable into and out of a position to be used adjacent said door, said seat being adapted to retain said door in closed position when in use and to release said door when not in use.

5 In testimony whereof we have hereunto set our hands in the presence of the subscr-

ing witnesses, on this 8th day of February A. D., 1910.
